UNITED STATES PATENT OFFICE.

WILLIAM A. HEIDE, OF DETROIT, MICHIGAN.

CARBURETOR.

Application filed October 1, 1919. Serial No. 327,779.

To all whom it may concern:

Be it known that I, WILLIAM A. HEIDE, a citizen of the United States, residing at Detroit, in the county of Wayne and State of Michigan, have invented a new and useful Carburetor, of which the following is a specification.

This invention relates to carburetors. One of the objects is to provide simple and efficient valve mechanism under the constant control of the operator whereby the supply of fuel in desired quantities to the carburetor mixing chamber is effected.

With the foregoing and other objects in view, which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention.

In the accompanying drawings the preferred form of the invention has been shown.

In said drawings

Figure 1 is a plan view of the carburetor.

Figure 2 is a section on line 2—2, Figure 1.

Figure 3 is a section on line 3—3, Figure 2.

Figure 4 is a section on line 4—4, Figure 3.

Referring to the figures by characters of reference, 1 designates a member having one or more pockets or chambers 2 therein each of which has an air inlet port 3. A conduit 4 is connected to this member and has an air inlet 5 at one end and a fuel outlet 6 at its other end. A spring pressed vent valve 7 is connected to the conduit and arranged in the conduit is a channeled member 8, the channels being in communication with the respective pockets or chambers 2. A slideable throttle valve 9 extends into the member 1 and is adapted to work transversely of the conduit 4, this valve, in the structure shown, being provided with blades or tongues 10 slideable within the pockets and having recess 11 in their free ends. The tongues or blades are of different lengths and the recess there-

in are adapted to be brought successively to position within the conduit 4.

Opening into the member 1 is a supply pipe 12 discharging into a distributing passage 13 and extending from this passage are branches 14 opening into the respective air inlet ports 3. Needle valves 15 or the like are arranged in the branches 14 and serve to control the flow of fuel into the pockets or chambers 2.

Intersecting the branches 14 is a transverse bore 16 having a screw thread on the wall thereof. This thread is engaged by an exteriorly threaded valve 17 having a passage 18 therethrough adapted to register with one of the branches 14. A threaded bore 19 extends into the valve 17 from one end and receives an exteriorly threaded valve 20, there being a passage 21 through the two valves 17 and 20 adapted to register with a second branch 14. A threaded bore 22 extends into the valve 20 from one end and receives an exteriorly threaded valve 23 and a passage 24 extends through the three valves 17, 20 and 23 and is adapted to register with the other branch 14.

Extending from the outer ends of the valves 17, 20 and 23 are crank arms 25, 26 and 27, respectively, each of which is provided at its free end with an inwardly extending finger 28'. A shifting plate 28 is slideable on the member 1 and has a slot 29 through which the projecting ends of the valves extend. Formed in this plate is a longitudinal slot 30 having an oblique end portion 31 and into this slot projects the finger 28' on the arm 25. Another longitudinal slot 32 is formed in the plate and has an intermediate oblique portion 33 and into this slot projects the finger 28' on the arm 26. Another longitudinal slot 34 is formed in the plate and has an intermediate oblique portion 35 and into this slot projects the finger 28' on the arm 27. The slots are so located relative to each other that when the plate is drawn in one direction the oblique portion 31 of the slot 30 will shift the arm 25 so as to rotate the valve 17 and open the passage 18 to the branch 14. During this movement the fingers 28' on the other arms 26 and 27 are sliding in the longitudinal end portions of the slots 32 and 34. As the plate continues to slide the finger 28' on the arm 26 enters the oblique portion 33 of slot 32 and rotates 110

valve 20 so as to open the passage 21 to its branch 14. Still further movement of the slide or plate will bring the finger 28 of the arm 27 into the oblique portion 35 of the slot 34 and open the passage 24 to its branch. When the plate 28 is moved in the opposite direction the movement of the valve is reversed successively and the flow of fuel to the branches 14 is cut off gradually. The plate 28 is connected to the throttle valve 9, as shown at 36 so that the valves will all work in proper relation, the throttle valve gradually cutting down the flow of fuel as the rotary valves are operated in the manner described.

For the purpose of priming the engine a group of passages 37 is extended to the upper portion of the conduit 4 or, in other words, to the conduit at a point near its outlet, these passages communicating with the passage 13 and being controlled by a rotary valve 38 under the control of the operator. When the valve is opened fuel will be delivered in separate small jets so that it will be more thoroughly mixed with the air than should the same amount of fuel be delivered in a single jet.

By threading the valves one within the other they are given a relative longitudinal movement during their relative rotation so that the passages through the valves are contracted gradually at the time they are being rotated out of register with the passages 14.

What is claimed is:—

- 35 1. In a carburetor, the combination with separate stationary fuel passages, of nested screw threaded valves in engagement with each other and mounted for independent and simultaneous rotation, said valves having passages therethrough normally registering with each other and with the fuel passages, and means for simultaneously and separately rotating the valves to impart relative annular and longitudinal movement thereto to move the passages in the valves gradually into or out of register with each other and with the corresponding stationary passages.
- 40 2. In a carburetor, the combination with separate stationary fuel passages, of a tubular valve in screw threaded engagement

with the carburetor structure and provided with interior screw threads, there being a passage through said valve movable into and out of register with one of the stationary fuel passages, a screw threaded tubular valve within and engaging the interior threads of the first named valve, there being normally registering passages extending through the two valves normally registering with a second stationary fuel passage, said second valve being interiorly screw threaded, a screw threaded valve seated within and engaging the interior threads of the second valve, there being normally registering passages extending through all of the valves and normally registering with a third stationary fuel passage, and means for successively and simultaneously rotating the valves to gradually bring the passages therein into or out of register with each other and with the corresponding stationary passages.

3. In a carburetor structure, the combination with separate stationary passages for discharging fuel, of an exteriorly and interiorly screw threaded valve in threaded engagement with the structure and having a diametrical passage therethrough movable into register with one of the fuel passages, a tubular exteriorly and interiorly screw threaded valve in threaded engagement with the first named valve, there being normally registering diametrical passages within the two valves movable into and out of register with a second fuel passage, and a third screw threaded valve within and in threaded engagement with the second tubular valve, there being diametrical passages within all of the valves normally aligning with each other and with a third fuel passage, and means for actuating the valves to control the flow of fuel through the stationary passages.

In testimony that I claim the foregoing as my own, I have hereto affixed my signature in the presence of two witnesses.

WILLIAM A. HEIDE.
